UNITED STATES PATENT OFFICE.

HERBERT PRICE LAVENDER, OF WALSALL, ENGLAND.

AUTOMATICALLY-OPENING SCREWING-DIE.

1,309,141.

Specification of Letters Patent.

Patented July 8, 1919.

Application filed June 29, 1918. Serial No. 242,522.

To all whom it may concern:

Be it known that I, HERBERT PRICE LAVENDER, subject of His Majesty the King of Great Britain and Ireland, residing at 65 5 Bridge street, Walsall, in the county of Stafford, England, have invented new and useful Improvements in and Connected with Automatically - Opening Screwing - Dies, of which the following is a specification.

10 This invention has reference to automatically opening screwing dies and to the die head or holder for holding and operating the same, the said die head or holder and the dies being adapted for use in a turret 15 lathe or the like with the die holder carried by the turret or other equivalent part so as not to revolve, or carried by the lathe spindle so as to revolve therewith.

My invention is of that type in which 20 the half dies are adapted to be closed by the operator to their set position for work and to be opened clear of the work by the action of a stop arresting the forward movement of part of the die head when the required 25 length of thread has been formed, means being provided for the micrometric adjustment of the dies and for making two or more screwing cuts of different depths with one setting of the dies.

30 The objects of my invention are to simplify the construction and arrangement of the parts of screwing dies and die head of the said type and particularly so that the die holder will have a minimum width so 35 that when carried on the turret or the like of a turret lathe the die head will readily pass between two tool posts on the cross slide to operate on the revolving work carried by the head-stock. Also I so arrange the dies 40 and the parts which carry them that there is no fear of the dies being choked or their sliding parts injured by the swarf. Also the parts of the die head can readily be taken apart for inspection of the dies or for 45 other purposes.

I will describe my invention by referring to the accompanying drawings of which:—

Figure 1 is a side elevation of a self-opening screwing die head and dies constructed 50 and arranged in accordance with this invention;

Fig. 2 is a front elevation of the same;

Fig. 3 is a sectional side elevation of the same;

55 Fig. 4 is a sectional side elevation of the same but showing the die carrier moved for-

ward and the dies opened to release the work;

Fig. 5 is a part sectional plan of the same;

Fig. 6 is a part front sectional elevation 60 of the same taken on line X X of Fig. 1;

Fig. 7 is a front elevation of the same showing the dies open;

Fig. 8 is a front elevation of the worm 65 wheel part of the same;

Fig. 9 is a front elevation, side elevation and plan of one of the half dies separately;

Fig. 10 is a front elevation of the bottom 70 half die and the side plates and accessories by which it is carried, and

Fig. 11 is a side elevation of the same.

In my invention the die head or holder consists of two main members which I will call respectively the body A and the die carrier B. The body A is a block made with 75 a backwardly projecting tubular shank 1 (detachable from or in a piece with the body A) adapted to be fixed in the turret or other tool holder of a lathe. The die carrier B has a backwardly projecting tubular or other shank 2 adapted to fit and slide in the hole or bearing 3 in the front of the body. This hole 3 is continued through the body A from front to back concentric with the axial center line of the head, and in the back part 80 of the hole the shank 1 is inserted and fixed. Suitable means are provided to prevent the die carrier B from turning in the body A such for instance as the parallel sided peg 4 which is fixed in a hole 5 in the die carrier B and projects from the back of the same and engages in a corresponding hole 6 85 in the body A. The die carrier B has a dovetailed or other equivalent parallel sided die-way 7 (Fig. 5) along its front face so as to accommodate the pair of half dies marked 90 respectively 8 and 9 (one of which is shown separately in Fig. 9) each formed with a dovetailed or other suitably shaped part 10 projecting from the back face and adapted 95 to slide up and down the die-way 7. The screw threaded portion 11 of the dies are situated and project at the front of the die-way 7 the dies being beveled up at each side at 12 forming clear passages for the escape of swarf clear of the die-way 7. The dies 8, 9, are moved nearer together or 100 farther apart equally at each side of the center line of the die head and dies by means of a double cam 13 formed on a spindle 14 arranged parallel with and above the center line of the dies and mounted in a bearing 105

110

15 in an upper extension part of the die carrier, this cam 13 acting between the top of the upper half die 8 and a block or bridge piece 16 which by the screws 17 is fixed to 5 two side plates 18, 19, situated at the sides of the die carrier B. To the lower ends of each of these side plates the other half die 9 is connected by the cross pin 20 which passes through holes in the side plates 18, 10 19, and through a corresponding hole 21 in the half die 9. The two coiled wire springs 22 arranged at the sides of the side plates 18, 19, connect the upper half die 8 to the upper 15 portions of the side plates 18, 19, and keep the bridge piece 16 in contact with the cam so that the latter will thus cause the half dies 8, 9, to move in opposite directions either to their open or to their closed positions when the shaft 14 and the cam 13 are 20 turned in the one or the other direction. The side plates 18, 19, are preferably arranged to fit close along the two sides of the die carrier B which latter is the same width as the half dies 8, 9, and is as narrow as the 25 dies will permit for their range of work. Fixed on the back end of the cam spindle 14 there is an upstanding lever 23 which carries a lateral projection 24 (see Figs. 4 and 5) adapted to engage against the edge 30 25 (Fig. 8) of an adjustable catch piece 26 which is fixed on the face of a worm wheel or worm wheel sector 27 which is mounted to revolve loosely on a spindle 28 which latter is mounted in a bearing 29 formed in 35 the body A. The pin 28 has a pin 28^x fitting in a recess in the worm wheel 27. This worm wheel sector 27 engages with a worm 30 on a transverse worm shaft 31 mounted in bearings formed on the body A and furnished with a head 32 which is micrometrically divided at 33 so that by turning the head 32 the worm shaft and worm 30 and worm wheel sector 27 can be turned in the 40 one or the other direction to adjust the position of the catch piece 26 and the degree of the closing of the dies. The micrometric divisions 33 register with a mark on the body A.

The back end 35 of the worm wheel spindle 50 28 is screw threaded and furnished with a locking nut 34 by which the worm wheel sector 27 can be locked against the face of the bearing 29 when the desired adjustment of the catch piece 26 has been attained. The two coiled wire springs 36, 37, arranged at the sides of the die head A and having their ends connected respectively on to the ends of the cross pin 20 and to split studs or the like 38 fixed to and projecting 55 from the sides of the body have the effect of drawing the die carrier B and the body A together and permit of the die carrier B moving forward slightly independently of the body A in the operation of the dies as 60 65 hereinafter described.

These springs 36 are however not material and they may be placed in other positions or be dispensed with if desired.

The combined dies and die head above in part described act as follows:—

The closing of the half dies 8, 9, to the correct amount to form the screw is first adjusted by turning the micrometrically divided head 32 of the worm spindle which turns the worm wheel sector 27 and adjusts 75 the edge 25 of the catch piece 26 thereof and the lever 23 and cam spindle 14 and cam 13 and also the corresponding amount to which the half dies 8, 9, are closed when the die head is set as in Figs. 1, 2, 3, and 5 with 80 the lateral projection 24 of the lever engaging against the edge 25 of the catch piece 26. When the revolving work has been screwed into the dies to the desired amount and the travel of the turret or other tool 85 holder has been arrested by a stop (as is usual) the forward movement of the body part A ceases, but owing to the screw threads of the dies engaging with the work, the forward movement of the die carrier B 90 continues for a short distance until the lateral projection 24 of the lever 23 has ridden off the catch piece 26 of the worm wheel sector 27 (see Figs. 4 and 7) and then the 95 springs 22 cause the top half die 8 and the cross bar 16 to act upon and turn back the cam 13, and the spindle 14 and the half dies 8, 9, fly open as in Fig. 7 and release the work. After the body A with the dies have 100 been traveled back clear of the work the lever 23 has to be pulled forward from the position shown in Fig. 7 to that shown in Fig. 6 so that the projection 24 will then have passed the edge 25 of the catch piece and the 105 springs 36, 37, will draw the die carrier B back into the body A (as in Figs. 1, 2, 3, 5, and 6), so that the lateral projection 24 of the lever will again engage with the edge 25 of the catch piece 26 and the dies 8, 9, are 110 now again closed ready for the next operation.

In order that at one setting of the dies they can be arranged to take two or more cuts on the same piece of work, so as for instance to first take a roughing cut with 115 the dies at a certain distance apart, and then for the dies to be closed slightly nearer together to take a finishing cut, the lateral projection 24 of the cam lever 23 is preferably made adjustable thereon so that it can 120 at will be caused to give slightly different angular positions to the cam lever 23 and cam 13 and a corresponding increased closure of the dies 8, 9. To this end said lateral projection 24 is not formed upon the 125 side of the lever 23 itself but is formed on a slide 39 which is tangential to the worm wheel sector 27 and is carried on a part 40 of the cam lever 23 and is slidably adjustable thereon by means of an eccentric 41. 130

which engages in a cross groove 42 on the slide 39, this eccentric being formed with an outstanding lever arm 43 and being mounted on a transverse pin 44, (see Figs. 4, 5, 5 and 6) which passes through the cross plate 47 into the hole 48 in the bracket part of the lever 23. Said plate 47 fits on the face of the cam 41 and is secured in place by the screw 49 and by the handle part of the lever 10 23 passing through the plate and through a slot 50 in the slide 39.

Thus after a cut on the work has been taken with the dies 8, 9, with the lateral projection 24 in a certain position and en- 15 gaging with the edge 25 of the catch piece 26 of the worm wheel sector, then if desired one two or more deeper cuts can be taken at the same setting of the micrometer 33, as before the next cut is taken, the slide 39 and 20 its lateral projection 24 are moved in slightly by turning the eccentric 41 and thus slightly altering the angular position of the lever 23, and slightly increasing the closure of the dies 8, 9, and imparting a deeper cut 25 to the thread which has been formed on the work.

The springs which hold the die carrier B to the body A are preferably two coiled wire springs 36, 37, as above described ar- 30 ranged at the sides of the body of the die carrier the ends of these springs being connected respectively to the body A and to the die carrier B.

The preferred construction is for the back 35 ends of the springs 36, 37, to be each connected to a cross wire loop or the like fitting in a transverse hole in the body A the ends of these loops projecting at the sides of the body. The front ends of these springs 36, 40 37, are snapped on to the grooved ends of the cross pin 20. Thus when the front ends of these springs 36, 37, have been disconnected from the ends of the pin 20 the die carrier B complete with the various parts 45 connected as aforesaid thereto, is free to be removed from the body A and can as readily be replaced and the ends of the springs 36, 37 snapped on to the projecting ends of the hinge pin 20. The connection of the ends of 50 the two springs 22 from the top of the side plates 18, 19, to the sides of the half top die 8 is preferably made by the end coil of each spring being connected on to pins 53 near the top of the side plates and the other 55 ends of the springs being connected to two wire loop like pegs 54 which are inserted in a hole 55 passing through from side to side of the top die 8 and there retained by the tension of the springs 22. Thus without re- 60 moving the carrier B from the body A the dies 8, 9, can very readily be removed for examination or for changing or grinding by simply pulling these loop like pegs 54 out of the hole 55 and also disconnecting the 65 lower springs 36, 37, from the cross pin 20

of the bottom die and then turning the two side plates 18, 19, and the top cross block 16 forward clear of the cam 13 so that the bottom die will then slip down out of the die way so as to be removed with the side 70 plates 18, 19, and cross block 16 and springs 22 and pegs 54 as shown in Figs. 10 and 11. The top die 8 can then be similarly removed by being slipped down out of the die way 7. Thus the dies 8, 9, can readily be removed 75 and changed or replaced and adjusted without employing any spanner or separate tool for the purpose. The top half die 8 is preferably made as a counter-part of the bottom half die so that either can be used in either 80 position.

The accompanying drawings illustrate what I consider to be the best way of carrying my said invention into practice but it is to be understood that my invention is not 85 limited to the precise details shown except as required by the claims as these can be varied to some extent without departing from the nature of my said invention.

What I claim as my invention and desire 90 to secure by Letters Patent is:—

1. In a combined die head and automatically opening screwing dies of the type described, the combination of a body member, a die carrier slidably mounted on the body 95 member and having a cross guide on its front face, a pair of half screw dies mounted in said cross guide, a cross block, a cam mounted on the die carrier and adapted to act between one of the half dies and said 100 cross block, two side plates connected to the other half die, a spring for keeping the half die and the cross block in contact with the cam, a die setting lever carried on said cam, a lateral projection on said lever, a worm 105 wheel carried by the body member, a catch plate on said worm wheel and adapted to be engaged by said projection, and a worm gearing coacting with said worm wheel for adjusting the same, the arrangement being 110 such that the turning of the die-setting lever in one direction turns the cam to a predetermined position so that the dies are closed together and the die setting lever is retained in such position by engaging with said catch 115 plate from which it is adapted to be released by the body stopping at the termination of the threading process and moving the dies and die carrier forward on the body member.

2. A combined die head and automatically opening screwing dies according to claim 1, in which the lateral projection of the setting lever is made adjustable thereon so as to close the dies nearer together without 125 altering the setting of the dies, substantially as set forth.

3. In a combined die head and automatically opening screw die, the combination of a die carrier formed with a dovetailed die- 130

way on its front face, a pair of half screwing dies slidably mounted in said die-way so as to advance toward or recede from one another, a double acting cam carried on the die carrier, a setting lever on said cam, a cross block, said cam acting between one of the half dies and the cross block, two side plates carried by said cross block and con-

nected to the other half die, and two coiled wire springs connecting the other half die to the side plates and keeping said half die and cross block in contact with the cam.

In testimony whereof I have signed my name to this specification.

HERBERT PRICE LAVENDER.
